(57) **CLAIM**

The ornamental design of a dog harness, as shown and described.

DESCRIPTION

FIG. 1 is a left and front perspective view showing the ornamental design of the claimed dog harness; FIG. 2 is a bottom view thereof;

FIG. 3 is a rear view thereof;

FIG. 4 is a right side view thereof;

FIG. 5 is a left side view thereof;

FIG. 6 is a top view thereof;

FIG. 7 is a bottom view thereof;

FIG. 8 is a left and front perspective view thereof, shown in a condition of use worn by a dog;

FIG. 9 is a top view in a flat configuration thereof; and,

FIG. 10 is a bottom view in a flat configuration thereof.

The dash-dash broken lines upon the dog harness in FIGS. 1 to 10 are for the purpose of illustrating stitching and form no part of the claimed design. The dashed lines of FIG. 8 that present a dog depict environmental subject matter and form no part of the claimed design.

1 Claim, 10 Drawing Sheets
